BEAM CLAMP BODY

Raymond M. Rumble, Girard, Ohio, assignor to Michigan Hanger Company, Hubbard, Ohio

Filed May 10, 1972, Ser. No. 252,154

Term of patent 14 years

Int. Cl. D8—08

U.S. Cl. D8—235

FIG. 1.

FIG. 2.

FIG. 4.

FIG. 3.

FIGS. 1 and 2 are perspective views looking at the top and bottom, respectively, showing my new design of a beam clamp body;

FIG. 3 is a longitudinal sectional view taken along the line 3—3 of FIG. 1; and

FIG. 4 is a perspective view, similar to FIG. 1, showing a modified design, the only difference over FIG. 1 residing in the rounded forward portion of the upper arm.

I claim:

The ornamental design for a beam clamp body, substantially as shown and described.
